UNITED STATES PATENT OFFICE.

HUBERT R. HUMPHREY, OF KALAMAZOO, MICHIGAN.

DESIGN FOR A GAS HEATER.

● 60,989.

Specification for Design.

Patented May 23, 1922.

Application filed September 27, 1921. Serial No. 503,622. Term of patent 14 years.

To all whom it may concern:

Be it known that I, HUBERT R. HUMPHREY, a citizen of the United States, residing at Kalamazoo, in the county of Kalamazoo and State of Michigan, have invented a new, original, and ornamental Design for Gas Heaters, of which the following is a specification, reference being had to

the accompanying drawing, forming part thereof.

The figure is a front perspective view of a gas heater, showing my new design.

I claim:

The ornamental design for a gas heater, as shown.

HUBERT R. HUMPHREY.
